Patented Apr. 1, 1919.

UNITED STATES PATENT OFFICE.

THOMAS KEPPEL NORTH, OF WESTMINSTER, LONDON, ENGLAND, ASSIGNOR TO VICKERS
LIMITED, OF WESTMINSTER, ENGLAND.

SUBMARINE MINE.

1,299,011.

Specification of Letters Patent.

Patented Apr. 1, 1919.

Application filed June 21, 1917. Serial No. 176,061.

To all whom it may concern:

Be it known that I, THOMAS KEPPEL NORTH, a subject of the King of Great Britain, residing at Vickers House, Broadway, 5 Westminster, in the county of London, England, have invented certain new and useful Improvements in or Relating to Submarine Mines, of which the following is a specification.

10 This invention relates to submarine mines particularly those of the kind having firing gear comprising a spring controlled striker head which is connected to its rod or stem in such a manner that it will become detached at a suitable period during the detraction of the said rod and will be impelled forward by the spring to explode the mine. In such mines when they are inter-connected by cables or the like, the 15 connecting cable is attached directly to the striker rod or to a member rigidly connected thereto with the result that the said rod is under more or less constant reciprocatory movements, owing to recurrent increase and decrease in the tension of the 20 connecting cable due mainly to the action of the sea currents; these reciprocatory movements may lead to the stuffing box through which the striker rod passes becoming worn and thereby allowing sea water to leak into the mine.

According to the invention the connecting cable is attached to a spring controlled member which is connected to the striker 35 rod in such a manner that the said rod will not be actuated until the connecting cable has been subjected to a predetermined tension such as would result from the impact of a ship with the said cable. The said member is preferably connected to its spring through the intermediary of a device which, after a certain movement of the member has taken place, will become detached from the said member so that the spring will not 40 impede the final or firing movement of this member.

In order that the said invention may be clearly understood and readily carried into effect the same will be described more fully

with reference to the accompanying drawings, in which:—

Figure 1 is an elevation showing more or less diagrammatically a mine constructed in accordance with the invention, and

Fig. 2 is a vertical section on an enlarged scale of the upper portion of the mine.

A is the mine casing, A' is the striker rod and A² is the connecting cable of the mine. B is the aforesaid spring controlled member and B' is the device by which the 60 said member is connected to its spring. C is a stop member that normally locks the firing mechanism against firing movement, and C' is the anchor or sinker cable connected to this stop member.

In the example shown the member B is in the form of a thimble slidably mounted in a casing B². This thimble is arranged with its base outermost and its open end contiguous to the upper part of the mine. 70 The base receives the connecting cable A² and the open end is formed with an internal flange b to constitute an abutment for a pin a passing laterally through the outer end of the striker rod. In the normal position of the parts, this pin is situated as shown some distance from the flange b so as to enable a certain amount of free axial movement to occur between the thimble and the striker rod. The spring b' that controls the thimble surrounds it and abuts at its upper end against the casing B² and at its lower end against the aforesaid device B'. This device comprises a ring which surrounds the lower end of the thimble and is detachably connected to the said thimble by a number of pins b², b² slidably carried in transverse holes in the ring. The inner ends of the pins are more or less pointed or rounded and are disposed in correspondingly shaped holes, or in a circumferential recess, in the lower part of the thimble. The outer ends of the pins bear against the internal wall of the casing B² which thus holds the pins in engagement with the thimble. At a suitable distance from its lower end the casing is formed with an internal circumferential groove b³. When the thim-

ble is retracted sufficiently to bring the pins opposite this groove they are pressed outwardly by the spring owing to the pointed or rounded formation of their inner ends 5 and the ring B' is thereby disconnected from the thimble; the spring thus ceases to exert pressure upon the thimble. Shortly after the ring has become disengaged from the thimble the flange b on the latter comes 10 against the pin a on the striker rod A' so that continued movement of the thimble retracts the striker and permits the firing of the mine. The striker head a' is shown as being connected to the striker rod by an arrangement of pins similar to that above described, although this connection might be 15 established by a shear pin as is well understood.

The aforesaid casing B² is provided with 20 a flange B³ whose inner part is disposed contiguous to the upper part of the mine and whose outer part is rounded to constitute a suitable bearing surface for the connecting cable, the flange being of such formation as 25 to make the casing as a whole of substantially conical shape. This arrangement prevents the connecting cables, when two or more are employed, from becoming entangled and also insures that the pull on 30 the thimble B shall be at a definite angle to the axis thereof irrespective of the position of the cable or cables in relation to the mine.

The aforesaid stop member C is constituted by a plunger mounted in the casing 35 B² and normally lying across the upper end of the thimble B. This plunger is carried by a spring controlled arm or lever C² pivoted at C³ to the casing and connected to the anchor or sinker cable C' which passes 40 through an eye A³ (Fig. 1) carried by the lower part of the mine. The plunger is locked in its operative position by a plug C⁴ of sal-ammoniac or other soluble substance so that the plunger cannot be 45 displaced to its disengaging position until the said plug has become dissolved. The plug is held in position by a screw C⁵ engaging with the casing and bearing against the outer portion of the plug, this screw being 50 formed with suitable apertures to enable the sea water to have access to the plug. The spring controlled arm or lever C², the plunger C and the soluble plug C⁴ are disposed within the aforesaid flange B³ of the casing, 55 the cable C' passing through a hole in the said flange.

The lower portion of the casing B² is screw threaded externally to engage with the usual collar A⁴ by which the tube a⁴ containing the detonator and striker is attached to the mine. The said casing together with its parts can readily be attached to existing mines in place of the usual firing arm or lever and its parts which are usually situated at the lower part of the mine with the

eye A³ at the top. It will thus be observed that in converting the mine from one of the impact type into one of the connected type the mine itself has been inverted as is shown by Fig. 1. The interchangeability of mines 70 provided for by the improvements is a feature of considerable practical importance.

What I claim and desire to secure by Letters Patent of the United States is:—

1. In a submarine mine of the connected 75 type, the combination with the firing mechanism, of a member to which the connecting cable is attached, and means interposed between said member and the firing mechanism whereby said member will actuate the 80 firing mechanism only after the connecting cable has been subjected to a predetermined tension.

2. In a submarine mine of the connected 85 type, the combination with the striker rod of the firing mechanism, of a spring controlled member to which the connecting cable is attached, and means interposed between said member and the striker rod whereby said member will actuate the striker 90 rod only after the connecting cable has been subjected to a predetermined tension.

3. In a submarine mine of the connected 95 type, the combination with the striker rod of the firing mechanism, of a spring controlled member to which the connecting cable is attached, an abutment on said member and another abutment on said striker rod, said abutments being situated some distance apart so that they will come into contact 100 to effect the actuation of the striker rod only after the connecting cable has been subjected to a predetermined tension.

4. In a submarine mine of the connected 105 type, the combination with the striker rod and the striker head of the firing mechanism, of a spring controlled member to which the connecting cable is attached, means interposed between said member and the striker rod whereby said member will actuate the 110 striker rod only after the connecting cable has been subjected to a predetermined tension and means for liberating the striker head from the striker rod after the latter has been retracted a predetermined distance. 115

5. In a submarine mine of the connected 120 type, the combination with the striker rod of the firing mechanism, of a spring controlled member to which the connecting cable is attached, a device normally connecting said member to its spring, means for disconnecting the device from said member after the latter has been moved through a predetermined distance, and means for enabling a certain movement of the said member relatively to the striker rod to occur before the latter is retracted by said member.

6. In a submarine mine of the connected 125 type the combination of a casing, means 130

attached to the connecting cable and carried by said casing, for actuating the firing mechanism of the mine and means for attaching said casing to the mine in place of the corresponding mechanism of an impact mine.

7. In a submarine mine of the connected type, the combination with the firing mechanism, of a collar by which a tube containing the detonator and the striker of the fir-

ing mechanism is attached to the mine, of a casing, means attached to the connecting cable and carried by said casing, for actuating the firing mechanism of the mine, and means for attaching said casing to said collar in place of the corresponding mechanism of an impact mine.

In testimony whereof I affix my signature.

THOMAS KEPPEL NORTH.
